UNITED STATES PATENT OFFICE.

ABRAHAM MILLEN, OF BOSTON, MASSACHUSETTS, ASSIGNOR TO AMERICAN SYRUP CO., OF BOSTON, MASSACHUSETTS, A CORPORATION OF MASSACHUSETTS.

DESIGN FOR A JUG.

Application filed March 23, 1923. Serial No. 5,570. Term of patent 14 years.

To all whom it may concern:

Be it known that I, ABRAHAM MILLEN, a citizen of the United States, residing at Boston, in the county of Suffolk and State of Massachusetts, have invented a new, original, and ornamental Design for Jugs, of which the following is a specification, reference being had to the accompanying drawing, forming part thereof.

The figure is a plan view of a jug, showing my new design.

I claim:

The ornamental design for a jug, as shown.

ABRAHAM MILLEN.
